DESIGN FOR AN OVER-THE-SHOULDER
HANDBAG

Louis J. Berman, Brooklyn, N. Y.

Application February 23, 1939, Serial No. 83,161

Term of patent 3½ years

To all whom it may concern:

Be it known that I, Louis J. Berman, a citizen of the United States and resident of Brooklyn, New York, in the county of Kings and State of New York, have invented a new, original, and ornamental Design for an Over-the-Shoulder Handbag, of which the following is a specification, reference being had to the accompanying drawing, forming a part thereof, and of which Figure 1 is a view in edge elevation of an over-the-shoulder handbag showing my new design, and Fig. 2 is a view thereof in front elevation.

The front and rear sides of the handbag are alike in design.

The design is characterized by the combination of a handbag of the form shown, suspended at its upper end by a decorative knot connected to the end of a supporting stick in the manner illustrated.

I claim:

The ornamental design for an over-the-shoulder handbag, substantially as shown and described.

LOUIS J. BERMAN.
